UNITED STATES PATENT OFFICE

111,151

DESIGN FOR A PERCOLATOR URN OR SIMILAR ARTICLE

Raymond E. Patten, Bridgeport, Conn., assignor
to General Electric Company, a corporation
of New York

Application April 9, 1937, Serial No. 68,640

Term of patent 14 years

To all whom it may concern:

Be it known that I, Raymond E. Patten, a citizen of the United States, residing at Bridgeport, in the county of Fairfield, State of Connecticut, have invented a new, original, and ornamental Design for a Percolator Urn or Similar Article, of which the following is a specification, reference being had to the accompanying drawing, forming a part thereof.

The accompanying drawing shows in the single figure a perspective view of a percolator urn embodying my new design.

I claim:

The ornamental design for a percolator urn or similar article as shown.

RAYMOND E. PATTEN.
